UNITED STATES PATENT OFFICE.

PATRICK J. McSHANE, OF STAPLETON, NEW YORK.

DESIGN FOR A KNIFE FOR OPENING SEAMS.

SPECIFICATION forming part of Design No. 28,798, dated June 7, 1898.

Application filed May 6, 1898. Serial No. 679,964. Term of patent 7 years.

To all whom it may concern:

Be it known that I, PATRICK J. McSHANE, a citizen of the United States, residing at Stapleton, in the borough of Richmond, county of Richmond, and State of New York, have invented and produced a new and original Design for a Knife for Opening Seams, of which the following is a specification, reference being had to the accompanying drawings, which form a part thereof, and in which—

Figure 1 is a side view of a knife for opening seams, showing my new design; and Fig. 2 is an edge view.

The leading or material feature of my design consists in a flat member *a*, having a V-shaped notch *b* in its outer end edge, one side edge extending from said notch being rounded, as at *c*, and the other side edge straight, as at *d*. The respective V-shaped end edge *b* and the side edges *c* and *d* are beveled or inclined, as shown. The side

edges of the member *a* in rear of the curved edge *c* and the straight edge are shown with insets or recesses of curved contour, as at *e e'*, from which recesses the edges extend rearwardly in a straight line, as at *f*. From the rear end of the member *a* extends a cylindrical enlarged portion *g*. 25

Having described my invention, what I claim as new, and desire to secure by Letters 30 Patent, is—

The design for a knife for opening seams, substantially as herein shown and described.

In testimony that I claim the foregoing as my invention I have signed my name, in presence of the subscribing witnesses, this 14th 35 day of March, 1898.

PATRICK J. McSHANE.
